CLAIM

The ornamental design for a working light, as shown and described.

DESCRIPTION

FIG. 1 is a front view of a working light of my new design; FIG. 2 is a rear view of the working light thereof; FIG. 3 is a top view of the working light thereof; FIG. 4 is a bottom view of the working light thereof; FIG. 5 is a left view of the working light thereof; FIG. 6 is a right view of the working light thereof; FIG. 7 is a perspective view of the working light thereof; FIG. 8 is a perspective view of the working light thereof with the light shown in an extended position; FIG. 9 is a perspective view of the working light thereof with the hook detail in an extended position; and, FIG. 10 is a perspective view of the working light thereof with the end cap detail shown in a rotated position. The broken line showing is for environmental purposes only and forms no part of the claimed design.
